UNITED STATES PATENT OFFICE

140,141

DESIGN FOR AN ULTRAVIOLET STERILIZER

George E. Glatthar, University Heights, and Joseph Terr, Cleveland Heights, Ohio, assignors to The Art Metal Company, Cleveland, Ohio, a corporation of Ohio

Application March 23, 1944, Serial No. 113,014

Term of patent 14 years

(Cl. D83—1)

To all whom it may concern:

Be it known that we, George E. Glatthar and Joseph Terr, citizens of the United States and residents of University Heights, and Cleveland Heights, respectively, in the county of Cuyahoga and State of Ohio, have invented a new, original, and ornamental Design for an Ultraviolet Sterilizer, of which the following is a specification, reference being had to the accompanying drawing, forming a part thereof.

In said drawing, Fig. 1 is a perspective view of an ultraviolet sterilizer showing our new design;

Fig. 2 is a front elevational view; Fig. 3 is a top plan view; and Fig. 4 is a bottom plan view thereof.

The back or rear surface of the ultraviolet sterilizer is of plain flat form, and no view of this portion therefore appears.

We claim:

The ornamental design for an ultraviolet sterilizer, substantially as shown and described.

GEORGE E. GLATTHAR.
